FACE MASK FOR SURGEONS OR THE LIKE

Gerald J. Liloia, 369 Alden Way, North Brunswick, N.J.,
and William H. Bird, R.D. 1, Somerset, N.J.

Filed Mar. 21, 1962, Ser. No. 69,497

Term of patent 14 years

(Cl. D83—1)

FIG. 1 is a front elevation of a face mask for surgeons or the like showing our new design; the straps and face of a wearer shown in broken lines are included for illustrative purposes only;

FIG. 2 is a side view of the mask of FIG. 1;

FIG. 3 is a back view of the mask of FIG. 1;

FIG. 4 is a cross-sectional view taken along line 4—4 of FIG. 3;

FIG. 5 is a modified form of the face mask illustrated in FIGS. 1—4;

FIG. 6 is a side view of the mask of FIG. 5;

FIG. 7 is a back view of the mask of FIG. 5; and

FIG. 8 is a cross-sectional view taken along line 4—4 of FIG. 7.

The present application is a continuation in part of

application Ser. No. D. 62,890 filed November 18, 1960, and now abandoned.

We claim:

The ornamental design for a face mask for surgeons or the like, as shown and described.
